UNITED STATES PATENT OFFICE.

HARRY A. JOCHUMSEN, OF WHEELING, WEST VIRGINIA.

BOILER-CLOSURE FOR HAND-HOLES.

1,349,510.

Specification of Letters Patent. Patented Aug. 10, 1920.

Application filed December 26, 1919. Serial No. 347,287.

To all whom it may concern:

Be it known that I, HARRY A. JOCHUMSEN, a citizen of the United States, residing at Wheeling, in the county of Ohio and State 5 of West Virginia, have invented certain new and useful Improvements in Boiler-Closures for Hand-Holds; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

This invention relates to new and useful improvements in closures for hand holes in domestic hot water boilers, and consists of a simple device of this nature so arranged 20 that access may be had to the boiler for the purpose of removing scale, sediment, etc.

The invention comprises various details of construction, combination and arrangement of parts which will be hereinafter fully described, shown in the accompanying drawings, and then specifically defined in the appended claim.

My invention is illustrated in the accompanying drawings which, with the letters of 30 reference marked thereon, form a part of this application, and in which:

Figure 1 is a sectional view through the boiler and closure, and

Figs. 2 and 3 are detail views of the 35 closure plates disassembled.

Reference now being had to the details of the drawings by letter:

A designates a plate which is preferably convexed upon its face, which is adapted to 40 engage the inner concaved surface of a boiler in connection with which the device is used. Said plate is provided with an oval-shaped projecting portion B adapted to engage a similarly outlined hole in the boiler, said projecting portion designed to extend 45 through the wall of the boiler, and 3 is a

gasket fitted about the projecting portion of the plate and having an oval outlined opening therein adapted to bear against the face of the boiler adjacent to the opening 50 in the wall thereof.

A threaded rod is anchored at one end in a recess in said projecting portion of the plate and is adapted to extend through the opening in the boiler. A second plate 4 has 55 a convexed recessed face 5 adapted to conform to the projecting portion of the plate 1. The plate 4 is apertured for the reception of said threaded screw. A nut 5' is mounted upon the threaded screw and is adapted to bear against the plate 4 for the purpose of holding the two plates in clamped relation with each other, thus forming a water and steam tight joint for the hand opening. 60

By the provision of a device embodying 65 the features of my invention, it will be noted that a simple means is afforded whereby access may be easily and conveniently had to the interior of a boiler for the purpose of removing scale or sediment which may accumulate therein which otherwise, if not removed, would impair the efficiency of the boiler. After the foreign matter has been removed the plates may be clamped together 70 as described.

What I claim to be new is:

A stand boiler provided with an elliptical perforation near its bottom, an elliptical clamping member fitting said perforation and provided with a shoulder with clearance for a gasket and provided with a bolt extending centrally therethrough, said clamping member conforming in contour to said boiler, a complementary clamping member fitting upon said first clamping 75 member with its inner side conforming in contour to and closely fitting said portion fitting said perforation.

In testimony whereof I hereunto affix my signature.

HARRY A. JOCHUMSEN.
